UNITED STATES PATENT OFFICE.

ARTHUR HANNS, OF LEIPZIG-PLAGWITZ, GERMANY.

MACHINE FOR MANUFACTURING TUBULAR BODIES FROM PLASTIC SUBSTANCES.

Application filed June 8, 1926, Serial No. 114,550, and in Germany July 3, 1925.

My invention relates to machines for manufacturing tubular bodies such as toy whistles and the like from plastic substances such as sugar or chocolate, means being provided for inserting in these bodies wooden or other handles. It is an object of my invention to provide improved means for preparing such bodies for the reception of such handles or the like. To this end I provide one or several moulds and retractable cores adapted to cooperate with such moulds so as to form cavities in the hollow bodies.

In the drawings affixed to this specification and forming part thereof a machine embodying my invention is illustrated diagrammatically by way of example.

In the drawings,

Fig. 1 is a side elevation of the machine, and

Fig. 2 is an end elevation,

Fig. 3 is a section on the line 3—3 in Fig. 1, Fig. 4 is a plan view, and

Fig. 5 is an elevation of a core extractor.

Fig. 6 is a section on the line 6—6 in Fig.

25 3. Figs. 4 to 6 are drawn to a larger scale.

Fig. 7 is an end elevation, partly in section on the line 7—7 of Fig. 8, and

Fig. 8 is an axial section of a modified mould cylinder.

30 Fig. 9 is a view in section taken on line 9—9 of Fig. 1 and viewed in the direction of the arrows.

Referring to the drawings, 1 and 2 are mould cylinders secured on shafts 3 and 4,

35 respectively, journaled in uprights *a* and *b*. Rotation is imparted to the shaft 4 of the lower mould cylinder 2 by any suitable means (not shown) and is transmitted to the shaft 3 of the upper mould cylinder 1 through the

10 medium of gears 4' and 3'.

Cavities *c* and *d* are formed in the cylinders 1 and 2 and during the rotation of these cylinders the cavities in the cylinder will successively register in pairs. Grooves 11 extend from both ends of each cavity *c* in the cylinder 1, and similar grooves 11' extend from the ends of the cavities *d* in the cylinder 2. As the cylinder 2 is longer at one end than the cylinder 1, the grooves 11' are correspondingly longer at that end. Discs 5 and 24 of somewhat larger diameter than the cylinder 2 are seated on its shaft 4 at both ends of the cylinder and are provided with perforations for the reception of cores

50 6 and 26, respectively, which are adapted to reciprocate in the perforations under

the action of pull-back springs 8 and 28, and helical cams 9 and 25, respectively, which are secured to each of the uprights *a* and *b* and are cut away for a short distance 60 at the top as will appear from Fig. 3. The pitch of the cam for the cores 26 is less than that of the cam for the cores 6 as the cores 26 move through a shorter distance than the cores 6. A projection 27 extends into each 65 cavity *c* of the cylinder 1, as shown plainly in Fig. 6, with the object of forming the air-outlet of the whistle. This projection extends as far as the core 6 and displaces the plastic substance at that point. Obviously the projections 27 might as well be formed in the cavities *d* of the cylinder 2, or in both cavities, as desired.

In the drawings, 1 and 2 are mould cylinders secured on shafts 3 and 4, respectively, journaled in uprights *a* and *b*. Rotation is imparted to the shaft 4 of the lower mould cylinder 2 by any suitable means (not shown) and is transmitted to the shaft 3 of the upper mould cylinder 1 through the medium of gears 4' and 3'. The plastic substance, for instance a sugar solution is supplied by a chute 7 and a hopper 10 is arranged slightly in advance of the chute and charged with handles such as short wooden sticks for the whistles. These handles it discharges into the longer grooves 11' of the cylinder 2. A knurled roll 23 is carried by an arm 23' which is freely journaled on the shaft 3. This roll is arranged between the disc 5 and the cylinder 1 opposite the hopper, and retains any handles which might leave said hopper after the corresponding groove 11' has moved past it.

A cam drum 16 with a groove 17 and a pinion 16' are arranged in front of the upright *a*. Rotation is imparted to said pinion from the shaft 4 through suitable gearing (not shown). 90 A pin or roller 18 at the end of a double-armed lever 15 is inserted in the groove 17 (Fig. 2). The lever 15 is fulcrumed at 15' in a bracket *e* secured to the upright *a* and connected with a slide 14 through a link 14'. 95 A core extractor 12 and a push bar 13 for the handles extend in parallel from said slide toward the disc 5 of the cylinder 2.

The extractor 12 is shown on a larger scale in Figs. 4 and 5. Its end is provided with a 100 fork 19 comprising two teeth 20 and 21. When the cylinder 2 rotates, bosses 6' at the ends of the cores 6 enter between these teeth.

The operation of this machine is as follows:

The cylinders 1 and 2 rotate as indicated by the arrows in Figs. 2 and 3, and the cores 6 and 26 penetrate gradually into the cavities *d*, as they approach the gaps in the cams 8 and 25, and finally abut against each other as shown in Fig. 6, when a pair of cavities *c* and *d* are in register. Shortly before this occurs, the cavity *d* has been charged with

sugar solution from the chute 7, and, as at this time the cores have penetrated a considerable distance into the cavity, they do not expel the plastic substance but, on the contrary, 5 the plastic substance fills the space of the cavity which surrounds the cores. As shown in Fig. 6, the mould is completed by the two cavities *c* and *d*, the cores 6 and 26 and the projection 27 which shapes the air hole in the 10 whistle. As the rotation of the cylinder 2 continues, the bosses at the ends of the cores 6 and 26 glide off the corresponding cams and are forced into the gaps of the cams by their pull-back springs 8 and 28, respectively. 15 As regards the cores 26, the springs can be relied upon to retract the cores as these latter are buried in the plastic substance a short distance only and therefore, means for extracting the cores 26 are not provided, but 20 the function is not so reliable for the cores 6, and therefore the extractor 12 is now moved to the left in Fig. 1 by the groove 17 and the lever 15 and positively extracts the core 6 from the mould. As soon as the corresponding 25 groove 11' has been laid open by the retracted core 6, it is entered by one of the handles from the hopper 10, this handle, on continued rotation of the cylinder 2, being pressed into the groove by the knurled roller 30 23. Meanwhile the core 6 which was just extracted will have cleared the extractor 12 and will be engaged by the push bar 13, so that when the slide 14 is again advanced to the right by the groove 17 the core will be advanced pushing the handle into the cavity formed by the core 6. At the same time the extractor 12 will engage the core 6 of the succeeding mould. Some play must be provided so as to enable the pusher and the extractor to perform their functions while the cylinders 1 and 2 are rotating. The finished 40 whistle is now free and as the mold cylinder revolves it drops out of the machine.

In the design of a whistle it is necessary to 45 direct the air blown into the whistle, against the sharp edge of the whistle slot and to this end I may bevel the ends of the cores 26, as shown at 30, in Fig. 6, to provide an inclined surface in the finished whistle which will deflect the air from an axial direction toward 50 the sharp edge of the whistle slot.

Obviously, the rotation of the cores 26 about their axis must be prevented in this case. To 55 this end, the heads of the cores 26 are cut away on their outer edges at 31 and an angular flange 29 is formed on the cylinder 24 against which such cut-away or flattened edges 31 abut and hold the cores against rotation. Obviously, instead of being circular, as shown, 60 the head of the cores 26 may be of any suitable shape and the edges 31 may be straight or curved, as convenient.

Obviously, it is also possible to manufacture articles of the kind described without

handles or other insertions, and the mechanism for extracting the cores 6 may be eliminated without departing from the spirit of my invention, and I wish it to be understood that I do not desire to be limited to the exact details of construction shown and described for obvious modifications will occur to a person skilled in the art. 65 70

I claim:

1. Machine for manufacturing tubular bodies from plastic substances comprising a 75 pair of cooperating cylinders, each defining part of a mould cavity, means for rotating said cylinders so that said cavities combine into a complete mould, co-axial cores inserted in one of said cylinders and means for reciprocating said cores in opposite directions. 80

2. Machine for manufacturing tubular bodies from plastic substances comprising a pair of cooperating cylinders, each defining part of a mould cavity, means for rotating 85 said cylinders so that said cavities combine into a complete mould, a core inserted in one of said cylinders, a stationary helical cam adapted to advance said core into said mould, and separate means for retracting said core 90 from said mould.

3. Machine for manufacturing tubular bodies from plastic substances comprising a pair of cooperating cylinders, each defining 95 part of a mould cavity, means for rotating said cylinders so that said cavities combine into a complete mould, a core inserted in one of said cylinders, a stationary helical cam adapted to advance said core into said mould, said cam being partly recessed, and means 100 for retracting said core from said mould when it has been released by said recessed portion of said cam.

4. Machine for manufacturing tubular bodies from plastic substances comprising a 105 pair of cooperating cylinders, each defining part of a mould cavity, means for rotating said cylinders so that said cavities combine into a complete mould, cores inserted in one of said cylinders, stationary helical cams adapted to advance each core into said mould, one 110 of said cams being of greater pitch than the other, and means for retracting said cores from said mould.

5. Machine for manufacturing tubular 115 bodies from plastic substances comprising a pair of cooperating cylinders, each defining part of a mould cavity, means for rotating said cylinders so that said cavities combine into a complete mould, a core inserted in one 120 of said cylinders, means for advancing said core into, and separate positive means for retracting it from, said mould.

6. Machine for manufacturing tubular bodies from plastic substances comprising a 125 pair of cooperating cylinders, each defining part of a mould cavity, means for rotating said cylinders so that said cavities combine

- into a complete mould, a core inserted in one of said cylinders, means for advancing said core into, and positive and resilient means for retracting it from, said mould.
5. 7. Machine for manufacturing tubular bodies from plastic substances comprising a pair of cooperating cylinders, each defining part of a mould cavity, means for rotating said cylinders so that said cavities combine into a complete mould, a core, means for advancing the core into and extracting the core from the mold, and means for inserting a member into the cavity formed by the core in the moulded object.
15. 8. Machine for manufacturing tubular bodies from plastic substances comprising a pair of cooperating cylinders, each defining part of a mould cavity, means for rotating said cylinders so that said cavities combine into a complete mould, one of said cylinders defining a groove in continuation of said mould, a core adapted to be advanced and retracted in said groove and said mould, means for inserting a member in said groove, and means for advancing said member into said mould after said core has been retracted therefrom.
9. Machine for manufacturing tubular bodies from plastic substances comprising a pair of cooperating cylinders, each defining part of a mould cavity, means for rotating said cylinders so that said cavities combine into a complete mould, one of said cylinders defining a groove in continuation of said mould, a core adapted to be advanced and retracted in said groove and said mould, means for inserting a member in said groove, means for depressing said member into said groove, and means for advancing said member into said mould after said core has been retracted therefrom.
10. Machine for manufacturing tubular bodies from plastic substances comprising a pair of cooperating cylinders, each defining part of a mould cavity, means for rotating said cylinders so that said cavities combine into a complete mould, a disc arranged at one end of said cylinders, said disc being of larger diameter than said cylinders, a core inserted in said disc where it projects beyond said cylinder, and means for advancing said core axially into and for retracting it axially from said mould.
11. Machine for manufacturing tubular bodies from plastic substances comprising a pair of cooperating cylinders, each defining part of a mould cavity, means for rotating said cylinders so that said cavities combine into a complete mold, a core inserted in one of said cylinders, means for advancing said core axially into, and for retracting it axially from, said mould, and a projection in one of said cavities adapted to cooperate with said core so as to form a hole in said moulded object.
12. Machine for manufacturing tubular bodies from plastic substances comprising a pair of cooperating cylinders, each defining part of a mould cavity, means for rotating said cylinders so that said cavities combine into a complete mould, a core inserted in one of said cylinders and bevelled at its inner end, means for advancing said core into, and for retracting it from, said mould, and a projection in one of said cavities adapted to cooperate with said core so as to form a hole in said moulded object.
13. Machine for manufacturing tubular bodies from plastic substances comprising a pair of cooperating cylinders, each defining part of a mould cavity, means for rotating said cylinders so that said cavities combine into a complete mould, a core inserted in one of said cylinders and bevelled at its inner end, means for preventing rotation of said core, means for advancing said core into, and for retracting it from, said mould, and a projection in one of said cavities adapted to cooperate with said core so as to form a hole in said moulded object.
14. Machine for manufacturing tubular bodies from plastic substances comprising a pair of cooperating cylinders, each defining part of a mould cavity, means for rotating said cylinders so that said cavities combine into a complete mould, a core inserted in one of said cylinders and bevelled at its inner end, a head on the outer end of said core, said head being non-circular on part of its edge, a check on the cylinder in which said core is inserted, said check being adapted to cooperate with said non-circular portion so as to prevent rotation of said core about its axis, means for advancing said core into, and for retracting it from, said mould, and a projection in one of said cavities adapted to cooperate with said core so as to form a hole in said moulded object.
15. Machine for manufacturing tubular bodies from plastic substances comprising a pair of cooperating cylinders, each defining part of a mould cavity, means for rotating said cylinders so that said cavities combine into a complete mould, a core inserted in one of said cylinders and bevelled at its inner end, a head on the outer end of said core, said head being non-circular on part of its edge, an angular flange on the cylinder in which said core is inserted, said angular flange being adapted to cooperate with said non-circular portion so as to prevent rotation of said core about its axis, means for advancing said core into, and for retracting it from, said mould, and a projection in one of said cavities adapted to cooperate with said core so as to form a hole in said moulded object.
16. Machine for manufacturing tubular bodies from plastic substances comprising a pair of cooperating cylinders, each defining part of a mould cavity, means for rotating

said cylinders so that said cavities combine into a complete mould, a core inserted in one of said cylinders and bevelled at its inner end, a head on the outer end of said core, said head being non-circular on part of its edge, an angular flange on the cylinder in which said core is inserted, said angular flange being adapted to cooperate with said non-circu-

lar portion so as to prevent rotation of said core about its axis, a stationary helical cam arranged within said angular flange and adapted to advance said core into said mould, and means for retracting said core from said mould. ¹⁰

In testimony whereof I affix my signature.
ARTHUR HANNS.
